UNITED STATES PATENT OFFICE.

WILSON E. SYMONS, OF CHICAGO, ILLINOIS.

CAR STRUCTURE.

No. 866,404.

Specification of Letters Patent.

Patented Sept. 17, 1907.

Application filed March 30, 1907. Serial No. 365,486.

To all whom it may concern:

Be it known that I, WILSON E. SYMONS, a citizen of the United States, residing at Chicago, in the county of Cook and State of Illinois, have invented a new and 5 useful Car Structure, of which the following is a specification.

This invention relates more particularly to the underframing for railway cars, and the primary object of the present invention is to provide a novel structure, 10 in which a metallic end sill can be employed and all the associated parts, whether of wood or metal, can be effectively secured to or mounted upon the said sill, thereby providing a strong, durable and practicable structure.

15 The preferred embodiment of the invention is illustrated in the accompanying drawings, wherein:—

Figure 1 is a plan view of one end of the underframe of a car. Fig. 2 is an end view of the same. Fig. 3 is a detail vertical sectional view showing the manner of 20 securing the studding. Fig. 4 is a cross sectional view on the line 4—4 of Fig. 1. Fig. 5 is a horizontal sectional view on the line 5—5 of Fig. 3. Fig. 6 is a horizontal sectional view through the underframe. Fig. 7 is a cross sectional view through the coupler shanks. 25 Fig. 8 is a plan view showing a slightly modified form of coupler. Fig. 9 is a cross sectional view on the line 9—9 of Fig. 8. Fig. 10 is a detail view of one of the yoke sections. Fig. 11 is a detail end view showing the manner of mounting the coupler below the plane of the 30 end beam.

Similar reference numerals designate corresponding parts in all the figures of the drawings.

In the embodiment illustrated, an end sill is employed that is in the form of a metallic shell 12, the ends 35 of this shell having integral rearwardly extending arms 13 that are provided with longitudinal sill-receiving seats 14, said seats opening through the outer sides of the arms. The outer sills 15 have their ends engaged in the seats, and secured thereto by suitable bolts 16. 40 These sills terminate short of the outer ends of the seats, in which case, filling blocks 17 are placed therein, in order that the siding 18 may be fastened in place. The intermediate longitudinal sills 19 have their ends engaged between rearwardly extending ears 20 and suitably fastened in place. While these ears are shown in the drawings as being comparatively short, it will be evident that they may be extended to any length desired, and may be employed for securing metallic as well as wooden sills.

50 The upper wall of the shell is provided with a series of sockets 21 having in their rear edges offset seats 22. Studding 23, shown in Figs. 3 and 5, are provided with metallic feet 24 having hooks 25 at their lower ends,

which engage in the seats 21, and interlock with the front walls thereof. Spikes or other suitable fasteners 55 26 are driven into the sockets in rear of the hooks and maintain their interlocking engagement. These spikes are partly located in the seats 22, and said spikes are driven into core sections 27 located within the shell. The core sections 27 are located in sockets provided 60 in the end sill on opposite sides of an elliptical socket 28 formed in the shell, and divided therefrom by walls 28. Through this socket extends the shank 29 of a coupler 30. The coupler and shank may be of any well known type, and sufficient lateral play is allowed to 65 the shank in order to permit the said coupler to pass around curves and be coupled on curves. Coiled springs 31 are located in the socket on opposite sides of the shank, their rear ends bearing against the rear wall 32 of said socket, their front ends bearing against 70 horns 33 projecting on opposite sides of the shank. In the structure disclosed in Figs. 6 and 7, these horns are formed integral with the head of the coupler, but in case an old coupler is employed, the said horns may be provided by clamping upon the shank, yoke 75 sections 34, shown in Figs. 8, 9 and 10. These yoke sections have eyes 35 provided with slots 36, through which the holding bolts 37 pass. The slots permit a slight relative play between the sections and prevent shearing of the bolts. It will be observed that in both 80 forms, the rear sides of the horns are provided with seats 38 that receive the front ends of the springs.

In the embodiment of the invention disclosed in Figs. 1—10, the socket 28 is formed directly in the body of the shell, but in case the coupler is to be supported 85 below the end sill, said sill, is provided with a central depending bracket 39 comprising spaced depending ears 40 connected at their lower ends by a tie-bar 41. The socket 42 thus produced is elliptical in form, and contains the mechanism above described.

90 It will be observed that by the provision of the sockets in the end sill on opposite sides of the socket which receives the coupler, the end sill is materially lightened. In these two sockets, the core sections 27 are placed and retained for a purpose which will be clearly 95 evident by reference to Fig. 3 of the drawings. As a result of this arrangement, the top, bottom and rear wall of the end sill is of metal, but the front or outer wall is partly of metal and partly of wood. In other words, the end sill is substantially U-shaped in cross 100 section, as shown in Fig. 3. In the modification shown in Fig. 11, where the coupler is arranged below the plane of the end sill, only one core section is provided, but the end sill is of the same shape in cross section as in Fig. 1.

105 From the foregoing, it is thought that the construc-

tion, operation and many advantages of the herein described invention will be apparent to those skilled in the art, without further description, and it will be understood that various changes in the size, shape, proportion, and minor details of construction, may be resorted to without departing from the spirit or sacrificing any of the advantages of the invention.

Having thus fully described my invention, what I claim as new, and desire to secure by Letters Patent, 10 is:—

1. In a car structure of the character set forth, an end sill having integral rearwardly extending arms that project beyond the remaining portions of the end sill and constitute means for securing the outer longitudinal sills thereto, 15
2. In a car structure of the character set forth, an end sill having long integral rearwardly extending arms at its ends, said arms being provided with longitudinal sill-receiving seats, and rearwardly extending ears of less length than the arms located between said arms and being integral with the sill, 20
3. In a car structure of the character set forth, an end sill having integral rearwardly extending arms provided with longitudinal sill-receiving seats having outer open 25 sides.
4. In a car structure of the character set forth, an end sill comprising a metallic shell having integral rearwardly extending arms provided with longitudinal sill-receiving seats having open sides and rear ends, longitudinal sills 30 having their ends located in the seats, and bolts securing the said ends in place.
5. In a car structure of the character set forth, the combination with a metallic sill having sockets in its upper side, of studding having hooked ends engaging in the sockets, and holding means engaging in the sockets behind the hooks, 35
6. In a car structure of the character set forth, the combination with a sill comprising a shell having sockets in its upper side, and a core located within the shell, of studding having hooked ends engaging in the sockets, and holding devices driven into the sockets behind the hooked end, 40
7. In a car structure of the character set forth, the combination with a sill comprising a metallic shell having 45 sockets in its upper side, and a core located within the shell, of studding including metallic feet having hooked ends detachably engaging in the sockets of the shell, and holding devices driven into the sockets behind the hooked ends.
8. In a car structure of the character set forth, the combination with an end sill comprising a metallic shell having rearwardly extending terminal arms provided with longitudinal seats in their outer sides, said shell having sockets in its upper wall and being provided with an elliptical socket, of longitudinal sills having their ends secured in the seats of the arms, studding having hooked lower ends engaged in the upper sockets, a core located in the shell, holding devices driven into the sockets in rear of the hooked end and engaging the core, a coupler having a shank slidably extending through the elliptical socket, springs located in the socket on opposite sides of the shank, and horns extending from opposite sides of the shank and bearing against the outer ends of the springs, 50
9. In a car structure of the character set forth, an end sill having integral rearwardly extending arms at its ends provided with longitudinal sill receiving seats and rearwardly extending sets of spaced ears projecting from the rear side of the sill between the arms and constituting means for fastening intermediate longitudinal sills to the end sills, said ears being shorter than the arms, 55
10. In a car structure of the character set forth, an end sill comprising a metallic shell having integral rearwardly extending arms at its ends, said arms being provided with longitudinal sill receiving seats having outer open sides, 75 integral rearwardly extending sets of spaced ears pro-

jecting from the rear side of the end sill between the arms, and a core located in the shell.

11. In a car structure of the character set forth, an end sill having integral rearwardly extending arms constituting means for securing the outer longitudinal sills thereto, and sockets in its upper side by which to fasten the studding, and studs having hooks at their lower ends that engage in the sockets, 80

12. In a car structure of the character set forth, the combination with a sill comprising a shell having sockets in its upper side, and a core located within the shell, of studding having hooked ends engaging in the sockets, and holding means passed through the sockets into the core and retaining the hooked ends in engagement, 85

13. In a car structure of the character set forth, the combination with a sill comprising a shell having sockets in its upper side, and a core located within the shell, and studding having engaging means interlocked with the sockets, 90

14. In a car structure of the character set forth, the combination with a sill comprising a metallic shell having sockets in its upper side, and a core located within the shell, of studding including metallic feet having hooked ends detachably engaging in the sockets of the shell, and means for holding the hooked ends in engagement, 95

15. In a car structure of the character set forth, the combination with a sill comprising a metallic shell having sockets in its upper side, and a core located within the shell, of studding including metallic feet having hooked ends detachably engaging in the sockets of the shell, 100

16. In a car structure of the character set forth, an end sill having integral rearwardly extending arms at its ends constituting means for securing the outer longitudinal sills thereto, and integral ears spaced apart between the said arms and projecting from the rear side of the sill for the attachment of the intermediate sills, said arms extending rearwardly beyond the ears, 110

17. In a car structure of the character set forth, an end sill having integral rearwardly extending arms provided with longitudinal sill receiving seats having outer open sides, and integral attaching means for the intermediate sills projecting from the rear side of the end sill and spaced apart between the said arms, 115

18. A metallic end sill having a coupler receiving opening and separate sockets opening through the front wall at opposite sides of the coupler opening for the reception of wooden core sections, 120

19. A metallic end sill having a central coupler receiving opening provided with end walls and separate sockets opening through the front wall at opposite sides of the coupler receiving opening for the reception of separate wooden core sections, 125

20. A metallic end sill made U-shaped in cross section, the top, bottom and rear walls being of one piece of metal, the front side being open for the reception of a wooden core, integral arms projecting rearwardly from the ends of the sill for the attachment of longitudinal sills, and integral ears projecting from the rear wall of the sill and spaced apart for the attachment of the intermediate sills, said arms being longer than said ears, 130

21. A metallic end sill made U-shaped in cross section, the top, bottom and rear walls being of one piece of metal, the front side being open for the reception of a wooden core, and studding mounted on the end sill and having interlocking engagement therewith, 135

22. In a car structure of the character set forth, a metallic shell having a central coupler receiving opening therethrough, and end walls defining the ends of the coupler receiving opening and extending to the front edge of the shell, the front side of the shell on opposite sides of the coupler receiving opening being open to receive wooden core sections, 140

23. In a car structure of the character set forth, a metallic shell having a central coupler receiving opening therethrough, and end walls defining the ends of the coupler receiving opening and extending to the front edge of the shell forming separate core receiving sockets, and separate cores located in the socket, 145

24. In a car structure of the character set forth, a metallic shell having a central coupler receiving opening, and separate wooden core sections located in the shell and having their inner ends terminating at said coupler receiving opening.
25. In a car structure of the character set forth, a substantially U-shaped metallic shell having a central coupler receiving opening therethrough and transverse intermediate walls forming sockets on opposite sides of the
- coupler receiving opening, and separate core sections fitted 10
in said sockets and terminating at said walls.
In testimony, that I claim the foregoing as my own, I
have hereto affixed my signature in the presence of two
witnesses.
